LOUIS J. STRAUSE AND OTTO SPAHR, OF PHILADELPHIA, PENNSYLVANIA, ASSIGNEES
TO STRAUSE GAS IRON CO., OF PHILADELPHIA, PENNSYLVANIA, A CORPORATION
OF PENNSYLVANIA.

BUNSEN BURNER.

1,118,696.

Specification of Letters Patent. Patented Nov. 24, 1914.

Application filed January 10, 1914. Serial No. 811,314.

To all whom it may concern:

Be it known that we, LOUIS J. STRAUSE and OTTO SPAHR, both citizens of the United States, and residents of Philadelphia, 5 county of Philadelphia, State of Pennsylvania, have invented certain new and useful Improvements in Bunsen Burners, of which the following is a specification.

Our invention relates to Bunsen burners 10 of the type particularly adapted for use in connection with gas stoves, incandescent gas lamps, self heating gas irons, and the like and has for its object to construct such burners in a manner to protect the custom- 15 ary flexible fuel conducting tube from the injurious effects of the heat produced by the burning fuel when the stove, lamp, iron or the like is in operation. Our invention further contemplates the provision of an im- 20 proved and simple connection for operatively attaching such tubes with said burners and further has for its purpose to improve the needle valve adjusting means in certain types of said burners. Our inven- 25 tion will be fully described hereinafter and the features of novelty will be pointed out in the appended claims.

Reference is to be had to the accompanying drawings which illustrate certain ex- 30 amples of our invention and in which—

Figures 1, 2, 3 and 4 are longitudinal sections, some partly in exterior, of different forms of our improvements and Fig. 5 is a horizontal-section on the line 5—5 of Fig. 1.

Referring more particularly to Fig. 1 of the drawings 10 represents an air hood which may be of any suitable or desired construction and as shown is externally screw-threaded to accommodate an air regulating

40 shutter 11 of any desired type adapted to co-operate with the usual air inlets 12 for regulating the amount of air admitted to said air hood for admixture with the gaseous fuel. The said hood 10 is further internally screw-threaded to receive the reduced neck 13 of a bushing 14 formed of fiber or other insulating material which is a non-conductor of heat. The customary metallic

45 nipple 15 is formed with an externally screw-threaded reduced neck 16 arranged to screw into the bushing 14 and is further provided with a central passage 17 terminating in an enlarged chamber 18 which is internally screw threaded at least at its inner end

50 to receive the screw-threaded neck 19 of the

nozzle 20. The said nozzle 20 in this form of our improvement is thus carried by the nipple 15 and may be made readily accessible when this is desired for any purpose by simply unscrewing said nipple 15 from said bushing 14. The air-hood 10 is detachably connected with the burner tube either of a gas stove, an incandescent gas lamp or of a self heating gas iron or the like in any customary manner as by screw-threading and the one end of the usual flexible tube 21 for supplying the fuel is slipped over the nipple 15.

With ordinary constructions the heat from the burner is conducted along the various metallic tubes forming part of the device and by coming into contact with the said fuel tube, which is usually constructed of rubber or a combination of rubber and some other substance, vulcanizes the said tube upon the nipple so as to prevent its removal therefrom without injuring the tube or otherwise injuriously affecting it. The life of the tube in such construction is thus materially reduced and the same is oftentimes rendered leaky and dangerous to use. In the present construction so far described the above objections are absolutely overcome and the said tube is effectively insulated against the effects of said heat by the insulating bushing 14 which absolutely arrests the conduction of said heat and prevents the same from reaching the tube 21. This is accomplished by locating the bushing 14 between the nipple 15 and the point at which the heat is generated, for instance, as is shown in Fig. 1 and described in the specification.

In the form shown in Fig. 2 a metallic nut 22 provided with a reduced externally screw-threaded neck 23 is screwed into the air hood 10 and is further formed with a central longitudinal passage 24 which is screw-threaded to receive the reduced neck 19 of the nozzle 20. In this form the said nozzle 20 is thus carried by said nut instead of being directly attached to the nipple 15 as in the first form described. The said nut in addition is provided with an internally screw-threaded recess into which the reduced externally screw-threaded neck 13^a of the insulating bushing 14^a is adapted to screw as clearly shown in Fig. 2, said bushing being formed with a channel 25 communicating with the passage 24 and the nozzle 21.

zle 20. In the form at present being described the nipple 15^a is formed with a reduced externally screw-threaded neck 16^a adapted to screw into an internally screw-threaded recess formed in the bushing 14^a.
5 As will be seen by referring to Fig. 2 the passage 17^a of the nipple 15^a connects with the channel 25 and thus establishes communication between the nozzle 20 and the source of fuel supply through the medium of the tube 21 which in this instance also has its one end slipped over the said nipple 15^a. Thus as in the form shown in Fig. 1 the insulating bushing 14^a by being located between the nipple 15^a and the point at which 10 heat is generated completely protects the tube 21 from the effects of said heat.

In the form shown in Fig. 3 the entire nipple 15^b is constructed of a material which 20 is a poor conductor or a non-conductor of heat and is provided with a reduced externally screw-threaded neck 16^b adapted to screw directly into the air hood 10. In this form as in the form illustrated in Fig. 1 25 the nipple is provided with a passage 17^b terminating in an enlarged chamber 18^b into which the screw-threaded neck 19 of the nozzle 20 is screwed. It will readily be seen that in the form now being described the 30 entire nipple 15^b being made of heat insulating material protects the tube 21 from the effects of the heat produced, the said tube in this case also having its one end slipped over said nipple.

35 In Fig. 4 we have illustrated a type of burner in which a needle valve is used in combination with the nozzle to regulate the flow of fuel to the air hood. In said figure a metallic tube 26 has a reduced externally 40 screw-threaded neck 27 which is screwed into the air hood 10 and which is internally screw-threaded at least at its one end to receive the externally screw-threaded reduced neck 13^c of the insulating bushing 14^c. The 45 said bushing 14^c is further formed with a reduced neck 13^d upon which an externally screw-threaded metallic ring 14^d is secured in any suitable manner, the neck 13^d preferably projecting slightly beyond the ring 14^d 50 as clearly shown in Fig. 4. In the form being described the flexible tube 21^a instead of being slipped over a nipple as in the previous forms has its one end secured to a sleeve 21^b provided with an annular flange 21^c upon which a coupling ring 21^d is rotatably mounted or swiveled, said ring being held against separation from the sleeve 21^b by means of an annular flange 21^e which cooperates with the flange 21^c as will be clearly 55 apparent from an inspection of Fig. 4. The coupling ring 21^d is internally screw-threaded and is adapted to be screwed upon the screw-threaded ring 14^d by being rotated upon the sleeve 21^b. This rotation of the 60 ring 21^d to connect the tube 21^a with the

burner will draw the flanged end 21^c of the sleeve 21^b against the projecting end of the neck 13^d of the bushing 14^c and thus firmly secure the tube and burner together, the projecting end of the neck 13^d acting as a packing 70 to secure a fuel tight joint and making it unnecessary to use a washer or other packing ring. By making the coupling ring 21^d rotatable relatively to the sleeve 21^b and tube 21^a the said tube may be readily connected 75 with the burner without any twisting of the tube 21^a so that the tube is protected against injury from this twisting, and from any other cause and the opposite end of said tube may be connected with the source of 80 fuel supply before the tube and burner are connected if this should be desired. At the same time an absolutely rigid connection between the tube and burner is secured and the danger of accidental separation thereof 85 is entirely done away with. The bushing 14^c in the form described is also provided with a longitudinal channel 25^a whereby communication between the tube 21^a and the burner is established. It will be seen that in this 90 form also the insulating bushing is located between the tube 21^a and the point at which heat is generated so that said tube is protected against the injurious effects of said heat. In this last form a needle valve 27^a 95 coöperates with the nozzle 20 to regulate the supply of fuel to the air hood 10 and is under the influence of a spring 28 which tends to force said needle valve 27 out of and away from the exit opening of the nozzle 20. The said needle valve 27 is forced toward and into the said exit aperture by means of a cam surface 29 forming part of a stem 30 which extends through and is in screw-threaded engagement with a tubular 105 extension 31 located on the tube 26. The said stem 30 is provided with an operating head 30^a by means of which the stem is moved lengthwise of the extension 31 through the coöperation of the screw-threads 110 on said stem and extension and the surface 29 is moved relatively to the valve 27 to either move said needle valve into the exit opening of the nozzle or permit the spring 28 to force the said needle out of said opening. 115 In order that a fine degree of adjustment of the needle valve 27 may be obtained and that said valve may be rigidly held in any adjusted position we form the operating head 30^a with a knurled or milled peripheral edge 120 32 and provide a resilient detent 33 adapted to coöperate with said milled or knurled edge 32 as will be readily apparent from an inspection of Fig. 4. The said detent may be secured in operative position and as 125 shown is clamped between the end of the tube 26 and the end of the air hood 10. It will be seen that with this construction the rotative movement of the head 30^a and the movement of the cam surface 29 are posi- 130

tively controlled through the coöperation of the milled edge 32 and the detent 33 and in consequence a very delicate and fine adjustment of the needle valve 27 is possible. At 5 the same time the coöperation of the said milled edge and detent will rigidly maintain the said head 30 and the needle valve 27 in any adjusted position and will prevent unintentional or accidental disarrangement 10 thereof through vibration or from other causes.

It will be seen that all forms of our improvement provide for the absolute protection of the fuel conducting tube against the 15 effects of heat and at the same time we provide an improved and simple means for connecting said tube with the burner. In addition to this the needle valve adjusting means is improved in action and efficiency. It is 20 to be understood that the type of needle valve mechanism illustrated is only an example and that our improved detent and operating head may be operatively combined with other forms of such mechanism. It is 25 further to be understood that in all forms of our improvement the heat insulating means may be constructed of any suitable material and may comprise means other than the bushings shown and described and also that 30 the insulating means may be combined or indicated in Bunsen burners or the like of other constructions than those shown.

Various changes in the specific forms 35 shown and described may be made within the scope of the claims without departing from the spirit of our invention.

We claim:—

1. A Bunsen burner of the kind described comprising an air hood, a nozzle carrying

means connected with said air hood, a rigid 40 bushing of insulating material connected with said nozzle carrying means and a device adapted for connection with a fuel conducting tube carried by said bushing.

2. A Bunsen burner of the kind described 45 comprising an air hood, a nozzle carrying tube in screw-threaded engagement with said air hood, an insulating tube in screw-threaded engagement with said nozzle carrying tube and a device adapted for connection with a fuel conducting tube carried by said insulating tube.

3. A Bunsen burner of the kind described comprising an air-hood, a nozzle carrying tube connected therewith, a bushing of insu- 55 lating material connected with said tube and a screw-threaded ring connected with said bushing.

4. The combination of a Bunsen burner of the kind described, a bushing of insu- 60 lating material connected therewith, a screw-threaded ring carried by said bushing, said bushing having an end projecting beyond said ring, a fuel conducting tube, and a 65 coupling ring rotatably mounted on said tube and adapted for connection with said screw-threaded ring whereby the end of said tube is drawn against the projecting end of said bushing.

In testimony whereof, we have hereunto 70 set our hands in the presence of two sub-scribing witnesses.
